SLIDE FASTENER

Lajos Steiner, Neutral Bay, New South Wales,
Australia

Application December 4, 1951, Serial No. 259,851

2 Claims. (Cl. 24—201)

1

This invention relates to slide fasteners for connecting, attaching or coupling parts, structures or fabrics in a releasable manner. The usual forms of slide fasteners consist of two side or edge elements, each of which is secured along the two edges of the opening to be closed, and a sliding member to effect the engagement and disengagement of same. In these types one edge element is trapped into the other by gradually forcing them together and keeping them engaged by means of close tolerances between the two members.

The present invention has been devised to provide a new type of slide fastener which lends itself to a wide range of application, is easy to manipulate and not liable to failure. A further purpose of the invention is to furnish a more positive and safer form of fastening, yet allowing greater tolerances.

According to the present invention, the slide fastener consists broadly of three parts: the receiver element containing a jaw portion with an opening into the jaws at one side edge thereof, such element extending along the side of the opening in an article to which the fastener is to be fitted, and said jaw portion also containing a locking member or device; an injector element to be secured to the other side edge of the opening of the article and extending therealong, having an engaging formation along its outer edge to engage inside the jaw portion of said receiver element where it is locked in place by said locking member or device; and a slider, movably mounted on said receiver element, and directing the injector element in and out from the jaws of said receiver element.

In order that the invention may be fully understood, reference is made to the accompanying drawings wherein:

Fig. 1 is a perspective view of the receiver element,

Fig. 2 is a perspective view of the injector element,

Fig. 3 is a perspective view of the slider,

Fig. 4 is a perspective view of the locking member,

Fig. 5 is a perspective view of a modification of the locking member,

Fig. 6 is a perspective view of the assembly of the slide fastener with the slider shown in Fig. 3,

Fig. 7 is a section taken along line 7—7 of Fig. 6. Another embodiment of the invention is shown in Figures 8 to 14 in which:

Fig. 8 is a perspective view of the receiver element,

2

Fig. 9 is a perspective view of the injector element,

Fig. 10 is a perspective view of the slider,

Fig. 11 is a perspective view of the locking member,

Fig. 12 is a perspective view of a modification of the locking member,

Fig. 13 is a perspective view of the assembly of the slide fastener with the slider shown in Fig. 10,

Fig. 14 is a section taken along line 14—14 of Fig. 13.

Referring to Figures 1 to 7 inclusive, the receiver element is shown in Fig. 1. This is roughly of rectangular channel shape and may be formed in any suitable way, such as pressing or extruding, casting, or otherwise, of metal, plastic or other appropriate material.

The injector element is shown in Fig. 2, and 20 is made of any suitable material which ensures sufficient flexibility, such as metals and plastics.

While provision for attachment of either the receiver, or injector elements to an article is not shown in the drawings, this may be effected by 25 sewing, welding, riveting or otherwise, depending on the material to which the fastener is to be applied.

Fig. 3 shows slider —c—, and Figures 4 and 5 show the locking member —e— and —e1— respectively. When made of one piece, as in Fig. 4, it should be of flexible material, such as plastic. I prefer, however, to use it in the form shown in Fig. 5, consisting of several sections.

To fully understand the function of all members, it is advisable to consider Fig. 7 showing the fastener fully assembled. Ridge —b1— of the injector element —b— is located in the groove against the side —e2— of said locking member. This ridge —b1— may fit loosely or firmly in said groove —a1— according to tolerance required. Intermittent endwise fixations are possible by a series of shallow impressions and protrusions coinciding with said ridge and groove, although by blocking the ends of the receiver element —a— endwise movements can be eliminated. Said locking member —e— sits against and along face —a2— and is held in position against shoulders —a5— of receiver element —a— by spring —f—. As there is no possibility of the injector element dislodging said locking member —e—, the union of the fastener is positive and unreleasable without other means. Groove —a6— of said receiver element —a— may be used in mounting receiver element —a— 55 on the edge of the article to which slide fastener

is to be mounted. Spring $-f-$ is preferably a leaf spring and located in the upper cavity of said receiving element $-a-$ on top of locking member $-e-$. In the modification of locking member $-e1-$ shown in Fig. 5 groove $-e3-$ is provided to locate said spring $-f-$, although this is not absolutely necessary.

In Fig. 6 the fastener is shown in operation. By moving sliding member $-c-$ in the direction towards the rear of locking member $-a-$, the fastener will be opened, while reverse movement of the slider $-c-$ closes same. The process is the following: Slider $-c-$ is slidably mounted on receiver element $-a-$, and the inclined surface $-c6-$ located on said sliding member $-c-$, gradually dislodges area after area, or section after section of the locking member $-e-$ or $-e1-$ respectively, thus freeing section after section of ridge $-b1-$ and leading injector element $-b-$ in or out through opening $-c3-$. This opening $-c3-$ has a down and outward direction in the illustration shown.

Another construction embodying the invention is shown in Figures 8 to 14 inclusive in which injector element $-b-$, receiver element $-a-$, slider $-c-$ and locking member $-e-$ and $-e1-$ respectively are all similar to the corresponding parts shown in drawings Figs. 1 to 7, differing from same mainly in arrangement.

To fully understand this second embodiment of the invention shown in Figures 8 to 14, it is advisable to consider Fig. 14 showing the fastener in closed position. Ridge $-b1-$ of injector element $-b-$ is located in groove $-a1-$ of the receiver element $-a-$ and is trapped in said groove $-a1-$ by locking member $-e-$ or $-e1-$ which is located inside of the receiver element $-a-$. The locking member $-e-$ is actuated by spring or springs $-f-$ and sits below and along groove $-a1-$ of said receiver element $-a-$, and ridge $-b1-$ of said injector element $-b-$, positively blocking the only exit from said ridge. Provision is not shown for retaining said locking member $-e-$ within said receiver element $-a-$ in disengaged position, as this can be effected in many different and simple ways, such as ridges inside of the receiver member $-a-$.

Fig. 13 shows the fastener in operation. Moving slider $-c-$ in the direction towards the rear of locking member $-a-$ opens the fastener, and opposite movement closes same, as follows: slider $-c-$ is slidably mounted on the receiving element $-a-$, and the angular surface $-c6-$ located on the end of slider $-c-$ gradually dislodges section after section of locking member $-e-$ supported by leafspring $-f-$, thus freeing section after section of said ridge $-b1-$ and leading it in and up, or down and out, through opening $-c3-$ which is shaped to take in said ridge.

It is believed from the above description and

attached drawings that those skilled in the art will fully understand the construction and operation of the device which is readily adaptable for a great variety of applications. Of course, changes in the form or size of parts, or their arrangement may be made, different means for the mounting of the device to the surfaces to be joined may be selected, without departing from the spirit of the invention which is not limited to the specific mechanisms shown and described, and from which departures may be made within the scope of the accompanying claims.

What I claim is:

1. A slide fastener, having, in combination, a receiver element, an injector element and a slider; said receiver element consisting of an elongated strip of material divided into two jaws by a longitudinal opening, and having on its inside a longitudinal recess capable of receiving and retaining said injector element, and having on its inside a resiliently supported longitudinal locking member; said injector element consisting of an elongated strip of flexible material having, along one side, an elevated portion and being locked inside said receiving element into said longitudinal recess by said resiliently supported locking member; said slider consisting of a frame slidably mounted on said receiver element and of a guide member mounted on said frame and inserted in said longitudinal opening of said receiver member locally compressing said resilient support of said locking member, and guiding said elevated portion of said injector element in and out from said longitudinal recess of said receiver element.
2. A slide fastener, having, in combination, a receiver element, an injector element and a slider; said receiver element consisting of an elongated strip of material divided into two jaws by a longitudinal opening, and having on its inside a longitudinal recess capable of receiving and retaining said injector element, and having on its inside a resiliently supported longitudinal locking member, said locking member consisting of a plurality of identical sections; said injector element consisting of an elongated strip of flexible material having, along one side, an elevated portion, and being locked inside said receiving element into said longitudinal recess by said resiliently supported locking member; said slider consisting of a frame slidably mounted on said receiver element, and of a guide member mounted on said frame, and inserted into said longitudinal opening of said receiver member, locally compressing said resilient support of said locking member, and guiding said elevated portion of said injector element in and out from said longitudinal recess of said receiver element.
